TRAILER

Roger E. Deckrow, Alma, Mich., assignor to New Moon Homes, Inc., Alma, Mich., a corporation of Michigan

Application October 27, 1955, Serial No. 38,590

Term of patent 3½ years

(Cl. D14—3)

The dominant features of my new design reside in the appearance of the rear end section of the trailer, as illustrated in full lines.

I claim:

The ornamental design for a trailer, substantially as shown and described.
